YVES MARIE PAUL GASTON LE PRIEUR AND AUGUSTE LOUIS RICORDEL, OF PARIS,
FRANCE, ASSIGNEES TO PRECISION MODERNE, OF PARIS, FRANCE, A CORPORATION
OF FRANCE

METHOD AND DEVICE FOR ANTIAIRCRAFT FIRING

Application filed July 7, 1930, Serial No. 466,272, and in France July 9, 1928.

The present invention has for its object a line of sight for anti-aircraft guns such as machine guns and ordnance firing from ground.

Generally speaking, such lines of sight or correcting devices allow when a field glass or the like is directed towards the aircraft to give this field glass or the gun or a part parallel thereto the angular correction required for the projectile to hit the point in space where the aircraft is to pass after the time corresponding to the time of flight of the projectile.

The method and the devices used take automatically into account the correction corresponding to the displacement of the object and to the deformation of the projectile path with varying angles of sight, the correction corresponding to the action of the wind both on the target and on the projectile the correction in the range as measured by the telemeter during the time of flight, which range is increased or not by a complementary amount according as to whether it is desired 25 to fire on the target itself and to aim continuously at it or to produce in front of it a curtain fire which it would have to pass through during the volley if it were to continue moving in the same direction.

The geometrical constructions and the calculations used according to the method which is the object of the present invention will first be disclosed with reference to Figs. 1 to 7 of accompanying drawings, said method being practically executed in the apparatuses to be described later.

Figs. 1, 2, 3, 4 concern the corrections due to the movement of the target and the deformation of the projectile path.

Figs. 5 to 7 relate to the wind correction.

Fig. 8 is a geometrical figure allowing the principle of the apparatus to be better understood.

Fig. 9 is a side view showing the arrange-

ment on a gun-carriage of the different parts of the correcting device.

Figs. 10 and 11 are simplified vertical cross-sections perpendicular to each other of the correcting device, the part pertaining to the wind correction being removed for sake of simplicity.

Fig. 12 is a plan view of this part of the correcting device which provides this wind correction.

In the first place, referring to Figs. 1 to 4, A_0 is the position of the moving target termed hereinafter the aircraft at the moment of the firing of a round by the gun O . A is its location at the moment where it is met by the projectile, this is the "future target".

Supposing t is the time of flight of the projectile.

V the speed of the aircraft.

D_0 the distance to the position of the target at the start.

The vector A_0A is equal to Vt .

$OB = L$ is the length comprised between the trunnion of the gun and the vertical of point A , the length of this vertical AB being p corresponding to the lowering of the trajectory.

The method consists chiefly in reproducing homothetically at reduced scale the polygon $O A_0 A B$ with a suitable reduction scale.

Fig. 2 shows the figure in space $OA_0 A B$ reduced at the scale $1/L$ in which case

$$(1) \quad Oa_0 = \frac{D_0}{L}$$

$$(2) \quad a_0a = \frac{Vt}{L}$$

$$(3) \quad ab = \frac{p}{L}$$

$$(4) \quad Ob = 1$$

The calculating device will form this reduced polygon, this is made easier by admitting $p = f(L)$ which is perfectly true in

vacuo and sufficiently approximating truth under normal firing conditions.

The formula (2) gives the correction of displacement of the target during the time of flight t . In view of making the operation automatic and of reducing the number of attendants, it has been admitted also that $t=f(L)$ which is also perfectly true in vacuo. Consequently $p=f(t)$ or

$$\frac{p}{L} = f\left(\frac{t}{L}\right) \quad (5)$$

It is thus apparent that the distance D_o at the time of firing being known, the application of the formulæ (1), (2), (3) and (5) allows the automatic introduction of the values of p and t corresponding to the future distance without any other reading to be made beyond that of the distance D_o .

Turning now to Figs. 3 and 4 showing means for obtaining a complementary time interval for quick firing from a machine-gun or quick-firing ordnance the complementary time e is equal to half the duration of the firing of the gun and is added to the duration of travel so as to fire at a point in front of the position by the amount V_o .

The correction due to the displacement of the aircraft is calculated during the time $t+e$.

The correcting device will practically give body to Fig. 3 wherein:

$$O'a'_o = \frac{D_o}{L}$$

$$a'_o a' = V \frac{t+e}{L}$$

$$a'b' = \frac{p}{L}$$

$$o'b' = 1$$

Supposing short outbursts of fire are provided at small distances and long outbursts at large distances, experience shows it is possible to write:

$$\frac{t+e}{L} = K,$$

K being a suitable constant.

It should be noted that instead of the scale

$$\frac{1}{L}$$

adapted in Figs. 2 and 3 for reducing the polygon $OA_o AB$, it is possible to use the scale

$$\frac{1}{t+e}$$

of Fig. 4. For small distances a simple linear formula binds the amounts

$$\frac{L}{t+e} \text{ and } \frac{P}{t+e}$$

Referring now to Figs. 5 to 7, supposing W is the speed of the horizontal wind; the aircraft is carried by it from A to A_1 through a distance Wt to be geometrically added to the vector Vt .

To reach the point A_1 , it is necessary on account of the action of the wind on the projectile to direct the gun not towards A_1 but towards A_2 , $A_1 A_2$ being disposed against the direction of the wind and equal to Kwt .

Consequently:

(a) In case the known speed and direction of the aircraft are the speed in calm air and the direction of the frame, the horizontal correction to be made is $AA_2 = (1+K)Wt$ in the direction of the wind;

(b) In case the known speed and direction of the aircraft are the real speed and direction i. e. with reference to the ground, the horizontal correction to be brought is $A_1 A_2 = Kwt$ against the direction of the wind.

In the first case the correcting device will form at the scale

$$\frac{1}{L}$$

(Fig. 6) the triangle oA_1A_2 which becomes Oaa_2 wherein

$$aa_2 = \frac{Wt - Kwt}{L} = W(1-K) \frac{t}{L};$$

in the second case the triangle OA_1A_2 becomes Oa_1a_2 (Fig. 7) wherein

$$a_1a_2 = \frac{Kwt}{L}$$

A form of execution of the apparatus for executing the method according to the invention has been shown by way of example in Figs. 8 to 11.

Fig. 8 shows means for executing the polygon of Fig. 2; the direction of the vector

$$\frac{Vt}{L}$$

parallel to the path of the target is obtained by means of a horizontal and of a vertical plate connected in a manner such that a single operation allows the two following rotary movements to be performed:

(a) A rotation round the vertical axis yy' with a view to laying the angle between the azimuth of the gun and the horizontal projection of the path of the aircraft;

(b) A rotation in the vertical plane $y dy'$ containing this projection of the path of the aircraft with a view to laying down the angle $a a_0$ of the aircraft with the horizontal.

On the line thus obtained ax_1 a length aa_0 is borne which is equal to

$$\frac{Vt}{L}$$

The arrangement of the two plates is then submitted to a vertical movement

$$ab = \frac{p}{L};$$

5 *b* is a stationary point on the axis O_2 of the gun at a predetermined distance Ob of the trunnion which is taken as a unit for calculating

$$10 \quad \frac{Vt}{L} \text{ and } \frac{p}{L}.$$

15 These different amounts are formed mechanically by the devices shown in Figs. 9 to 11.

20 A frame 1 is automatically held vertical through the agency of a parallel motion comprising a stationary arm 2 forming an extension of the gun carriage head, a sight-bar 3 parallel to the axis of the gun and a connecting rod 4 integral with the frame 1, the fourth side being formed by the gun on the cradle of which is provided a pivot 5 for the connecting rod.

25 The frame 1 carries on its outer side a slide 6 wherein moves a slider 7 ending at its upper end with a horizontal circular plate wherein the sunwheel 9 carrying at its upper

30 part a rose 10 is adapted to rotate.

35 A pinion 11 meshes with the wheel 9. It receives its movement from a sliding Cardan-shaft 12 the other end of which carries a pinion 13 meshing with a stationary circular rack 14.

The gear ratio is such that the sunwheel 9 remains angularly stationary in space during all the azimuthal rotations of the gun carriage.

40 A target plate 16 adapted to rotate with reference to the plate 8 and the sun-wheel 9 is provided with a pointer 17. The radius leading to the pointer shows the intersection with the horizontal plane of the vertical plane 45 passing through the aircraft. The number read in front of the pointer 17 shows the direction of the aircraft. If the aircraft does not change its path, the pointer 17 gives out the same division of the "rose" during the 50 entire revolution of the gun-carriage.

55 A "rose" or more correctly "compass card" is a horizontal circular member or disk graduated in degrees or the like starting from a predetermined origin and one finds one's position in space in such a manner that the meridian plane (plane of the origin) of the "rose" passing through this origin, also passes through the geographical north or another known cardinal point. The point of origin 60 of the graduations bears the reference "North" or "N". The diametrically opposed point bears the reference "South" or "S", etc.

65 The plate 16 is provided with pistons 18 which engage an inner toothwork of the wheel 9 whereby the plate is driven by the

wheel after the plate has been given the desired angular starting position.

An arrow-shaped bar 19 serves to make the target plate 16 rotate according to the direction of movement of the aircraft when the latter changes its path. This bar is held as well known in gunnery parallel to the frame of the aircraft or to its path.

70 It may rock in the vertical plane so as to be parallel in space to the frame of the aircraft even if the flight is not horizontal. This control of the bar, in the vertical direction has for its result an instantaneous correction of the speed of the aircraft so as to take into account the action on it of a downward or upward direction of the aircraft.

75 It is known in effect that the speed of a downwardly moving aircraft increases and that of an upwardly moving aircraft is reduced. This result is accomplished as follows:

80 A circular vertical plate 20 rigidly secured to the directing bar 19, rotates with friction inside a circular recess of the object plate 16. Its axis of rotation is horizontal and crosses the vertical axis of the plate 16. A slider 21 passes through a guide in the plate 20 formed along a diameter parallel to the directing bar.

85 The slider 21 is provided with two knobs or projections of which one 22 engages an aperture in the vertical rod 23 ending with a rotula 34 corresponding to the point a_0 of Figs. 2 and 8; the other knob 24 engages the groove of a cam 25 disposed behind the plate.

90 The working of this arrangement is as follows:

95 (a) Any rotation of the cam 25 causes an advance motion of the knob 24 and consequently of the slider 21 in its groove which provides a varying eccentricity of the knob 22 and consequently of the rod 23;

100 (b) Any downward or upward movement of the aircraft corresponding to an obliquity of the slider in the guiding groove of the plate 20 has as a consequence a displacement 105 of the slider 21 under the action of the knob 24 moving in the groove of the cam stationary at the moment considered.

110 The curve chosen should be such as will prevent any jamming between mechanical parts. It depends on one hand, as stated, on the law supposed to govern the modifications of speed during sloping flight and on the other hand on the manner in which is calculated the correction due to the displacement of the aircraft. The cam serves together for the control of the eccentricity corresponding to the slope and of that corresponding to horizontal speed of the aircraft.

115 The preferred curve is a logarithmic spiral which has as an advantage the provision of a constant engagement angle between the cam and the corresponding projection. This spiral is suitably chosen so as to reproduce as far as possible the normal variation in speed 120

120

125

130

of the aircraft the path of which is not horizontal.

This logarithmic spiral affords means for giving the rod 23 an eccentricity corresponding to the horizontal displacement of the aircraft.

As illustrated in Fig. 2 this eccentricity should be

$$10 \quad r = \frac{Vt}{L}.$$

This means

$$14 \quad \log r = \log \frac{Vt}{L} = \log V + \log \frac{t}{L}$$

As the cam spiral is logarithmic, it is necessary to impart to it the sum of two rotations proportional respectively to $\log V$ and to $\log$

$$20 \quad \frac{t}{L}.$$

The cam is cut in a circular roller 25' outwardly toothed and meshing with a worm 26 controlled by the planet wheel of a differential 27 the frame of which is under the control of a pinion keyed to the shaft of a handle 28 adapted to move in front of a logarithmic scale of speeds. The other planet wheel receives, as will be explained hereinafter, a rotation proportional to

$$35 \quad \frac{t}{L}.$$

To the so-called "rotula" or universal joint 34 is pivotally secured the end of the rod 41 sliding in the sleeve 42 fitting in its turn in the socket of the cardan shaft 43 the horizontal axis of which is at a distance from the axis 40 equal to the length considered as the unit in the device so as to correspond to line O_2 in Fig. 2.

Obviously the distance along rod 41 between the rotula 34 and the axis 44 varies proportionally to

$$D_o$$

50 and corresponds to the distance Oa_o of Fig. 2. On the other hand it is obvious that to each value of D_o and of

$$\frac{D_o}{L}$$

corresponds only one value of L and consequently of

$$60 \quad \frac{t}{L}$$

as it has been supposed that $t=f(L)$. If

$$65 \quad \frac{D_o}{L}$$

and D_o are suitably combined, it is therefore possible to obtain

$$\frac{t}{L}$$

and to transmit it to the differential 27.

To this end the variations of

$$\frac{t}{L}$$

are transmitted through a flexible shaft 30 of the Bowden type secured to the end of the rod 41 and the sheath of which bears against the sleeve 42, to a hand 31 moving over a disc shaped abacus 32 provided with curves corresponding to the different distances D_o . This disc-shaped abacus is rotated through a worm and a gear train by a shaft 33 provided with a handwheel. This shaft controls through bevel pinions the rotation of the rod 38 carrying the above mentioned planet wheel of the differential 27.

The eccentricity of the projection 22 is thus caused to be proportional to

$$\frac{Vt}{L}$$

This projection drives the rod 23 which moves in the vertical aperture of the horizontal slider 35 sliding in a corresponding guideway of the plate 16 and disposed in the vertical plane containing the arrow 19.

The rotula 34 at the lower end of the rod 23 is on the other hand to be given a vertical motion equal to

$$\frac{p}{L}$$

This is obtained by giving the slider 7 the said motion.

The amount

$$\frac{p}{L}$$

may be obtained through an abacus giving out the curves depending on the distances and the angles of sight.

In the case of the firing of a machine-gun, it may be admitted as explained hereinabove that

$$\frac{p}{L}$$

is approximately equal to

$$f\left(\frac{t}{L}\right).$$

This allows to control the desired vertical motion through the shaft 33 the rotation of which is proportional to

$$\frac{t}{L}$$

The mechanical device described hereinafter is based on this method.

A cam 36 cut according to the law giving VK and the shaft 33 provides simply the vertical motion

$$\frac{p}{L}$$

- 5 is adapted to raise the roller 37 on the slider 7. The movement of the cam is obtained through a wheel 38 meshing with the worm 39 driven from the shaft 33 through bevel 10 pinions. The target plate is thus caused to rise through a distance

$$\frac{p}{L}$$

- 15 Consequently for a speed zero, the rotula 34 is at the intersection of the vertical axis of the plate 16 and of the horizontal axis of the shaft 40. For any value given to the speed and to the range, the rotula 34 will be 20 at the point given by the composition of the vectors

$$\frac{Vt}{L} \text{ and } \frac{p}{L}$$

- 25 as shown in Fig. 2.

The working of the apparatus is as follows:

- The attendant begins by directing the arrow 19 parallel to the direction of the aircraft either by sight if no measuring means are 30 at hand, or after reading on the rose 10 if the angle of the aircraft path may be given to him. The speed is then registered by bringing the handle 28 in front of the suitable scale, and the distance is similarly registered 35 by acting on the handwheel of the shaft 33 until the hand 31 arrives on the curve of the abacus 32 corresponding to the desired distance. This provides in the differential 27 the product

$$\frac{Vt}{L}$$

- 40 and causes the cam 25 to rotate through a suitable angle through the agency of the worm 26. The desired eccentricity of the rotula 34 is thus obtained and the sightglass is given the required correction. The layer has now only to return the sightglass on to the aircraft through the laying handwheels of the 45 gun-carriage and to keep it directed on to said aircraft.

If it is desired to fire by outbursts, the above mentioned formula

$$55 \quad \frac{t+e}{L} = K$$

being used, the apparatus may be simplified. In this case

$$80 \quad \frac{V(t+e)}{L}$$

- becomes VK and the differential 27 may be done away with. The scale over which moves 85 the handle 28 gives out the logarithms of

$$\frac{p}{L}$$

70

When it is desired to provide the wind corrections by means of the apparatus described (Fig. 12), the sunwheel 9 driven by the pinion 11 so as to remain stationary in space during the rotation of the gun-carriage, instead of having as in the case of Figs. 10 and 11, a circular bore wherein the plate 16 is adapted to rotate, contains a plate 51 frictionally held in said sunwheel 9. This plate has a slideway 52 for the slider 53 carrying 80 the plate 16 with the correcting parts such as the plate 20, the arrow 19 and the like.

The apparatus is made use of as follows:

Supposing the zero of the scale of the sunwheel 9 is directed towards the north and is 85 held thus through the rotation of the pinion 11, the slideway 52 is given a direction parallel to that of the wind by bringing for instance a hand integral with this slider way in front of the desired graduation of the 90 sunwheel 9. On the other hand, the speed of the wind is registered by moving the slider 53 along its slideway, said slider carrying for instance an index therefor moving in front of a suitable scale. 95

In the specification the term "abacus" indicates a system of lines drawn in a plane, in a system of predetermined coordinates, for determining a function graphically assuming, for example, that one has to determine a 100 function $z=f(x, y)$, this equation could be determined by tracing in a system of rectangular coordinates ox, oy , the curves $z=a, z=b, z=c$, etc. If it is desired to have the value of z corresponding to x_0, y_0 , it will be sufficient 105 to find the position of the point $M(x_0, y_0)$ relative to the above curves.

What we claim is:

1. An apparatus for the correction of anti-aircraft gun firing comprising two arms pivotally secured to each other one of which of constant length is parallel to the gun, a sight glass carried by the other arm and means for giving the outer end of said other arm a movement parallel to the movement of the object and equal to the path covered by it during a predetermined time at the desired scale and a vertical motion equal to the loss of height of the projectile passing through the end of said path with reference to the 115 axis of the gun at the same scale. 120

2. An apparatus for the correction of anti-aircraft gun firing comprising two arms pivotally secured to each other one of which of constant length is parallel to the gun, a sight glass carried by the other arm, a vertical rod pivotally secured to the outer end of the said other arm, a horizontal rotary plate, means for radially guiding the vertical rod in said plate, means for constrain- 130

ing said guiding means to remain parallel to the projection of the direction of motion of the target, means for causing the distance between the vertical rod and the center of the plate to be equal to the path covered by the target during the time of flight at a scale of

$$\frac{1}{L},$$

- 10 L being the distance measured along the axis of the gun between the gun and the vertical passing through the end of the path traveled by the target during the flight of the projectile and means for moving vertically the plate 15 by an amount equal to the loss of height of the projectile passing through the end of said path with reference to the axis of the gun at the same scale as above.

3. An apparatus for the correction of anti-aircraft firing comprising two arms pivotally secured to each other one of which of constant length is parallel to the gun, a sight glass carried by the other arm, a vertical rod pivotally secured to the outer end of said 25 other arm, a horizontal rotary plate, means for radially guiding the vertical rod in said plate means for constraining said guiding means to remain parallel to the projection of the direction of motion of the target, means 30 for causing the distance between the vertical rod and the center of the plate to be equal to the path covered by the target during the time of flight at a scale of

35 $\frac{1}{L},$

L being the distance measured along the axis of the gun between the gun and the vertical passing through the end of the path traveled 40 by the target during the flight of the projectile, a spirally grooved vertical cam, a part engaging same and controlling the transverse movements of the rod, means for keeping the cam parallel to the displacement of the target, means for rotating same and means for displacing the plate vertically by an amount 45 equal to the loss of height of the projectile passing through the end of said path with reference to the axis of the gun at the same 50 scale as above.

4. In an apparatus as claimed in claim 3 a slider pivotally secured to the rod, a vertical plate parallel to the cam along a diameter of which the slider is adapted to move and 55 means for keeping the said diameter parallel to the path of the target.

5. An apparatus for the correction of anti-aircraft firing comprising two arms pivotally secured to each other one of which of constant length is parallel to the gun, a sight glass carried by the other arm, a vertical rod pivotally secured to the outer end of said other arm, a horizontal rotary plate, means for radially guiding the vertical rod in said 65 plate, means for constraining said guiding

means to remain parallel to the projection of the direction of motion of the target, means for causing the distance between the vertical rod and the center of the plate to be equal to the path covered by the target during the 70 time of flight at a scale of

$$\frac{1}{L},$$

L being the distance measured along the axis 75 of the gun between the gun and the vertical passing through the end of the path traveled by the target during the flight of the projectile, a spirally grooved vertical cam, a part engaging same and controlling the transverse movements of the rod, means for keeping the cam parallel to the displacement of the target, an adding differential gear controlling the rotation of the cam and separate means for giving said gear elementary rotations equal to $\log V$ and $\log$ 80

$$\frac{t}{L},$$

V being the speed of the aircraft and t the 90 time of flight, and means for displacing the plate vertically by an amount equal to the loss of height of the projectile passing through the end of said path with reference to the axis of the gun at the same scale as above. 95

6. An apparatus for the correction of anti-aircraft firing comprising two arms pivotally secured to each other one of which of constant length is parallel to the gun, a sight glass carried by the other arm, a vertical rod pivotally secured to the outer end of said other arm, a horizontal rotary plate, means for radially guiding the vertical rod in said plate, means for constraining said guiding means to remain parallel to the projection of the 100 direction of motion of the target, means for causing the distance between the vertical rod and the center of the plate to be equal to the path covered by the target during the time 105 of flight at a scale of

$$\frac{1}{L},$$

L being the distance measured along the axis 115 of the gun between the gun and the vertical passing through the end of the path traveled by the target during the flight of the projectile, a spirally grooved vertical cam, a part engaging same and controlling the transverse movements of the rod, means for keeping the cam parallel to the displacement of the target, an adding gear controlling the rotation of the cam, means for giving said gear an elementary rotation equal to $\log V$, a plate 120 graduated in distances, means cooperating therewith for giving the gear a second elementary rotation equal to $\log$ 125

$$\frac{t}{L}$$

and means for displacing the plate vertically by an amount equal to the loss of height of the projectile passing through the end of said path with reference to the axis of the gun at the same scale as above.

7. An apparatus for the correction of anti-aircraft firing comprising two arms pivotally secured to each other one of which of constant length is parallel to the gun, a sight glass carried by the other arm, a vertical rod pivotally secured to the outer end of said other arm, a horizontal rotary plate, means for radially guiding the vertical rod in said plate, means for constraining said guiding means to remain parallel to the projection of the direction of motion of the target, means for causing the distance between the vertical rod and the center of the plate to be equal to the path covered by the target during the time of flight at a scale of

$$\frac{1}{L},$$

L being the distance measured along the axis of the gun between the gun and the vertical passing through the end of the path traveled by the target during the flight of the projectile, a spirally grooved vertical cam, a part engaging same and controlling the transverse movements of the rod, means for keeping the cam parallel to the displacement of the target, an adding gear controlling the rotation of the cam, means for giving said gear an elementary rotation equal to $\log. V$, a plate graduated in distances, common means cooperating therewith for giving the gear a second elementary rotation equal to $\log$

$$\frac{t}{L},$$

and for displacing the plate vertically by an amount equal to the loss of height of the projectile passing through the end of said path with reference to the axis of the gun at the same scale as above.

8. An apparatus for the correction of anti-aircraft firing comprising two arms pivotally secured to each other one of which of constant length is parallel to the gun, a sight glass carried by the other arm, a vertical rod pivotally secured to the outer end of said other arm, a horizontal rotary plate, means for radially guiding the vertical rod in said plate, means for constraining said guiding means to remain parallel to the projection of the direction of motion of the target, means for causing the distance between the vertical rod and the center of the plate to be equal to the path covered by the target during the time of flight at a scale of

$$\frac{1}{L},$$

L being the distance measured along the axis of the gun between the gun and the vertical

passing through the end of the path traveled by the target during the flight of the projectile, a spirally grooved vertical cam, a part engaging same and controlling the transverse movements of the rod, means for keeping the cam parallel to the displacement of the target, an adding gear controlling the rotation of the cam, means for giving said gear an elementary rotation equal to $\log. V$, a plate graduated in distance, means cooperating therewith for giving the gear a second elementary rotation equal to $\log$

$$\frac{1}{L},$$

70

75

80

85

a cam controlled by last mentioned means for displacing the plate vertically by an amount equal to the loss of height of the projectile passing through the end of said path with reference to the axis of the gun at the same scale as above.

9. In an apparatus as claimed in claim 3, means controlled by the gun-carriage for keeping the plate in a constant angular position in space.

10. In an apparatus as claimed in claim 3, means controlled by the gun-carriage for keeping the plate in a constant angular position in space and comprising a sunwheel, spring urged pistons making same integral with the plate and a gear train connecting same with the gun-carriage.

11. In an apparatus as claimed in claim 3, means for correcting the action of the wind comprising a slider carrying the plate and means for moving said slider in accordance with the wind direction and speed.

In testimony whereof we affix our signatures.
